UNITED STATES PATENT OFFICE.

JOHN G. ERICKSON, OF HADLEY, MINNESOTA.

SASH-FASTENER.

SPECIFICATION forming part of Letters Patent No. 396,150, dated January 15, 1889.

Application filed March 12, 1888. Serial No. 267,034. (No model.)

To all whom it may concern:

Be it known that I, JOHN G. ERICKSON, of Hadley, in the county of Murray and State of Minnesota, have invented a new and Improved 5 Sash Lock and Fastener, of which the following is a full, clear, and exact description.

My invention relates to a sash lock and fastener, and has for its object to provide a device automatic in its action, strong and durable, free from springs, simply attached, and which will hold the sash at any desired height, and lock the same when closed without possibility of its being pried open from the outside.

15 The invention consists in the construction and combination of the several parts, as will be hereinafter fully set forth, and pointed out in the claims.

Reference is to be had to the accompanying 20 drawings, forming a part of this specification, in which similar letters of reference indicate corresponding parts in all the views.

Figure 1 is a perspective view of the device applied to a window-sash. Fig. 2 is a longitudinal section through the same, illustrating 25 the parts in position to lock the window when closed; and Fig. 3 is a similar view illustrating the position of the parts when the window is held open.

30 In carrying out the invention the casing A is provided with a partial opening, a, in one side, extending from a point near the lower end to the top, and the wall below the said opening upon the inner side is made to incline downward, as illustrated at a' in Fig. 2.

Within the casing an angular gravity-bolt, B, is pivoted, the upper arm, which is the longer, being provided with an outwardly-projecting head, b. By reason of the long upper member of the bolt it naturally assumes a position illustrated in Figs. 1 and 2, the head extending from within the casing through the opening a. In order to throw the said long arm back into the casing, a slot, D, is cut in the face of the casing, intersecting the opening a and extending downward at an inclination parallel with the wall-surface a', as shown in Figs. 2 and 3, and within the casing a disk, D', having a serrated or otherwise 45 roughened exterior, is manipulated from the outside by means of a spindle, d, integral with the disk, which spindle, projecting through the slot D, is provided with a suitable knob or handle, E. The casing is preferably open 50 at the back.

In operation the device is attached to the side of the window-sash flush, or nearly so, with the inner edge, as shown in Fig. 1, being held by two screws, e e', only, one acting as a fulcrum for the angle-bolt and the other 60 serving as a stop, limiting the inner throw of the bolt.

When the devices are in the position shown in Fig. 2, the friction holder or disk D' serves to hold the upper end of the bolt B projected through the casing-opening a into the recess H, and the sash is thus positively locked against upward movement. To retract the bolt, the friction-holder D' is moved upwardly until it strikes the bolt above its pivot. The 70 sash may now be raised to any desired position, and the operator holds the handle E with the right hand and allows the sash to lower slightly. This will cause the friction-holder 75 to ride up the incline formed by the upper arm of the bolt until it is firmly wedged between the sashway and said upper arm, as shown in Fig. 3, and thus a sash-holder is formed.

Having thus described my invention, what I 80 claim as new, and desire to secure by Letters Patent, is—

1. A combined sash fastener and holder, consisting in a casing having an opening in one side, an inclined locking-bolt within the 85 casing and projecting, when thrown through said opening, to positively lock the sash when closed, a vertically and outwardly movable friction-holder, also in said casing in front of and below the bolt, whereby, when moved 90 vertically, said friction-holder will retract and ride up said inclined bolt and be forced simultaneously outward thereby through the said opening in the casing to hold the sash open, substantially as set forth. 95

2. A sash-fastener comprising a casing having a side opening and a downward incline in the lower end of said casing, a bolt pivoted between its ends in said casing, and a disk working on said incline and against the lower end 100 of said bolt to hold its upper end projected through the case-opening, substantially as set forth.

JOHN G. ERICKSON.
